Herbert G. Odgen
HIS ATTORNEY

UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

STEEL RETAINER.

Application filed July 10, 1925. Serial No. 42,645.

This invention relates to steel retainers, but more particularly to that type of retainer which may be secured to the front end of a rock drill to cooperate with a collar formed on the working implement for preventing ejection of the implement from the machine.

It is an object of this invention to produce a rugged steel retainer of simple design which is inexpensive to manufacture and efficient in operation.

Other objects will be in part obvious and in part pointed out hereinafter.

The invention consists of the combinations of elements, features of construction, and arrangement of parts having the general mode of operation, substantially as herein-after described and more particularly pointed out in the appended claims and illustrated in the accompanying drawing, in which

Figure 1 is a side view of the front end of a rock drill showing the retaining member in retaining position,

Figure 2 is a front view of a rock drill showing the retaining member in retaining position, and

Figure 3 is a perspective view of the retaining member.

Referring to the drawing, the invention is shown applied to a rock drill, only the front end of which is shown for purposes of illustration and in which a front head A is provided with lugs B having apertures C to receive suitable side bolts (not shown) for securing the front head A to the machine. In this instance, the front head A is centralized with respect to the machine by means of a front cylinder washer D, only a part of which is shown. Disposed within the front head is drill steel E having a collar F formed thereon for limiting the travel of the drill steel into the front head. Trunnions G are in this instance formed on opposite sides of the front head A and are offset from the longitudinal axis of the machine.

In accordance with the present invention, a one-piece retaining member H, formed to partly encircle the front head, has a pair of projections K at one end which are provided with suitable bearings L in the form of slots for the member H. The bearings L are preferably so formed as to fit loosely

over the trunnions G which in this instance serve as a pivotal support for the member H.

In order to prevent accidental ejection of the drill steel E from the front head A while the drill is in operation, a yoke O is formed at the front end of the member H to embrace the drill steel E in advance of the collar F. In this manner, if the machine is withdrawn while the percussive element is in operation, the drill steel E may be forced forwardly out of the path of the hammer piston, but since the yoke O forms a stop for the collar F, the shank end of the drill steel E will remain in the front head A in readiness for a succeeding operation.

To the end that the member H may be constantly held in the position shown in Figures 1 and 2, a lug P is formed on each side of the member H to extend beyond the side of the front head A when the member H is in retaining position. The lugs P are preferably provided with holes Q extending therethrough to receive a pin R. One end of the pin R is provided with a head S which serves as a convenient grip for the operator to insert said pin within the holes Q. A bulb T is formed on the opposite end of the pin R to prevent endwise movement of said pin within the holes Q. In this instance, cross slots U are cut longitudinally through the bulb to form spring fingers V for the purpose of permitting the bulb T to pass through the holes Q.

Suitable means are provided for preventing longitudinal movement of the member H with respect to the trunnions G. To this end, a bolt W is inserted transversely through each projection K and is provided with a suitable nut X for securing said bolt in position. The bolt W is preferably so arranged with respect to the trunnion G that when the member H and the bolt are in position, the bolt will contact with the trunnion G and thus form one side of the bearing.

In the operation of the device, if it is desired to remove or insert the drill steel, the pin R may be withdrawn from the lugs P and the member H may then be rocked on the trunnions G to the position shown in dot and dash lines in Figure 1. It will be observed that in this position, the yoke O of the retaining member H is withdrawn

from the path of the collar F and the steel may then pass the end of said yoke.

If desired, the pin R may be removed only from one lug and may then be moved longitudinally until the bulb T contacts with the inner face of the other lug. In this way the pin is prevented from contacting with the side of the front head A when the member H is rocked on the trunnions G and the pin R will be in readiness for insertion in the opposite lug when the member H is again placed in retaining position.

The advantages of this invention reside in the simplicity of construction and consequently it is inexpensive to manufacture and to maintain. A further advantage is that this construction permits of a rugged retaining member, capable of withstanding the rough usage to which devices of this character are ordinarily subjected.

I claim:

1. In a steel retainer for rock drills, the combination of a front head with a collared implement inserted into the front head, trunnions on the front head and offset from the longitudinal axis of the machine, a retaining member supported by the trunnions, and means insertable transversely through the retaining member to cooperate with the front head for holding said member in retaining position.

2. In a steel retainer for rock drills, the combination of a front head with a collared implement inserted into the front head, a pair of trunnions on the front head and offset from the longitudinal axis of the machine, a retaining member supported by the trunnions, lugs on opposite sides of said member, and means insertable transversely through said lugs to cooperate with the front head for holding said member in retaining position.

3. In a steel retainer for rock drills, the combination of a front head with a collared drill steel supported slidably by the front head, a pair of trunnions on the front head and offset from the longitudinal axis of the machine, an oscillatory retaining member, bearings on the member to cooperate with the trunnions for supporting said member, lugs on opposite sides of said member, and a removable pin insertable transversely through said lugs to cooperate with a side of the front head for holding said member in retaining position.

4. In a steel retainer for rock drills, the combination of a front head with a drill steel inserted slidably into the front head, a collar formed on said drill steel, a pair of opposed trunnions on the front head and offset from the longitudinal axis of the machine, an oscillatory retaining member, a

pair of bearings at one end of the member to cooperate with the trunnions for supporting the member, a yoke at the other end of the member to embrace the drill steel in advance of the collar for preventing ejection of the steel from the front head, lugs formed on opposite sides of said member between the bearings and the yoke, and a removable pin inserted slidably through said lugs cooperating with a side of the front head for holding said member in retaining position.

5. In a steel retainer for rock drills, the combination of a front head with a drill steel inserted slidably into the front head, a collar formed on said drill steel, a pair of opposed trunnions on the front head and offset from the longitudinal axis of the machine, an oscillatory retaining member, a pair of bearings at one end of the member to cooperate with the trunnions for supporting the member, a yoke at the other end of the member to embrace the drill steel in advance of the collar for preventing ejection of the steel from the front head, a pair of lugs formed on said member between the bearings and the yoke, a removable pin inserted slidably through said lugs cooperating with a side of the front head for holding said member in retaining position, a bulb on one end of said pin to prevent endwise movement of said pin, and spring fingers to permit the passage of the bulb through said lugs.

6. In a steel retainer for rock drills, the combination of a front head with a drill steel inserted slidably into the front head, a collar formed on said drill steel, a pair of opposed trunnions offset from the longitudinal axis of the machine, an oscillatory retaining member partly encircling the front head, a pair of bearings at one end of the member to cooperate with the trunnions for supporting the member, a yoke at the other end of the member to embrace the steel in advance of the collar for preventing ejection of the steel from the front head, bolts arranged transversely through the bearings and cooperating with the trunnions to hold the member against longitudinal movement, a pair of lugs formed on said member between the bearings and the yoke, a removable pin inserted slidably through said lugs cooperating with a side of the front head for holding said member in retaining position, a bulb on one end of said pin to prevent endwise movement of said pin, and spring fingers to permit the passage of the bulb through said lugs.

In testimony whereof I have signed this specification.

CHARLES C. HANSEN.
